UNITED STATES PATENT OFFICE

ROBERT HAGEBUSCH, OF BROOKLYN, NEW YORK

BOTTLE CLOSURE WITH MEANS FOR REMOVING THE PAPER COVERS

Application filed April 10, 1931. Serial No. 529,200.

The present invention relates to a household utensil and more particularly to a cover for milk bottles or the like.

Much difficulty is often experienced in removing the paper covers commonly used on milk bottles. Forks, knives or other tools must often be employed for that purpose as a result of which the cover is mutilated and ceases to close tightly.

10 One object of this invention is to provide a utensil which will form a durable, sanitary, tight closure or cover for a milk bottle or the like.

Another object is to so construct said device that it will also serve as a dispenser for the contents of the bottle.

A further object is to provide said device with means for removing the paper cover from the bottle before it is applied to the latter.

20 And still another object of this invention is to so construct the device that it will be simple and can be manufactured at low cost.

With these and other objects in view, my 25 invention comprises the novel construction, combination and arrangement of elements to be hereinafter more fully described, shown and defined in the appended claims.

In the accompanying drawing, which 30 forms part of this specification and in which similar reference characters denote corresponding parts:—

Fig. 1 is an elevation partly in section of my device illustrating its position on the 35 bottle when used as a cap remover;

Fig. 2 is an elevation partly in section of my device illustrating its position on a bottle when used as a stopper and dispenser;

Fig. 3 is a partial sectional elevation of the 40 dispensing end of my device;

Fig. 4 is a partial inner view of the lid on the dispensing end of my device; and

Fig. 5 is an elevational view of a modified 45 form of my device.

Referring to the drawing, 10 denotes a milk bottle of the conventional type having the usual rounded bead 11 at its mouth and an annular shoulder 12 in its neck portion on which the usual sealing paper cover 13 50 rests.

My device, according to the construction shown in Figs. 1-4, consists of a hollow tapered body 14 of sheet metal or any other suitable material and having at the upper end a spout 15 extending at an angle to the body portion, so that its dispensing end is offset from the longitudinal axis of the body portion, to facilitate the pouring out of the contents of said bottle 10. The mouth of said spout 15 is adapted to be closed by a movable lid in form of a cap shaped member 17. This cap bears a suitable tightening means 18 made of cork, rubber or other resilient material adapted in closed position to tightly bear on the mouth of the spout. The cap 17 is formed with or has attached to it an arm 19 whose free end constitutes a grasp. Intermediate the ends of said arm or grasp the latter is provided with eyes 19' whereby it is hingedly attached as at 20 to a projection 21 provided on the upper end of the spout 15. A spring 22 or other suitable means is provided for continuously urging said cap 17 into closing position. By the depression of the grasp 19 the lid can be 25 opened for dispensing the contents as indicated by dotted line position in Fig. 1.

The tubular body 14 may be provided with a plurality of circumferential annular corrugations, beads or ridges 14' and its bottom with an outwardly extending annular flange 14², to retain a washer 27 of rubber, cork or other resilient or expandible material adapted to be slidably mounted around said body 14. The washer may be conical 30 in shape and formed as a hollow body as shown whereby its resiliency may be increased.

In the modification of Fig. 5, the tubular body 14 has smooth walls 14³.

The diameter of said washer at its lower end is so admeasured that when said tubular body is passed into said neck portion, said washer as it is being pushed upwardly on said body will be compressed to produce a perfectly tight engagement between said body and mouth of the bottle. The washer in cooperation with the annular ridges 14' of said body will retain the device in position on the bottle.

As already stated the milk bottles generally come with the sealing paper covers 13. Before my device can be applied to the bottle it is necessary to remove said cover. Instead of resorting to knives, forks or the like, for the removal of the cover, I combine my device with a tool for removing the cover. To this end, a piercing pin 24 is pivotally mounted in said tubular body 14, for instance on a wire or rod 25 suitably fixed in the walls thereof and extending diametrically therethrough. Said pin may be curved to the arc of a circle having its center in said rod. This pin is carried by one end of a link member 26 which passes through an opening in the spout 15 and whose other end is pivoted to said lever 19. By the depression of said lever 19, said pin 25 is rotated in the dotted line position as shown in Fig. 1, causing it to pierce through the paper cover 13, so that when said device is lifted from the bottle, the paper cover will be picked up from the bottle.

In use, the device is inserted into the mouth 25 of the bottle and by depressing the lever 19 the piercing pin 26 is caused to pierce the cap 13. Thereupon, while holding the lever 19 down the device is lifted from the bottle and with it the cap 13 which on releasing the lever 19 can be pulled off the pin 24.

With this cover removed the device 14 may now be inserted into the mouth of the bottle and pushed down into the bottle neck as far as it will go. By reason of its tapered 35 shape the washer 27 will slide up the walls of said body and become tightly wedged against the walls of the bottle neck, thereby firmly securing the device in position within the bottle and rendering it leakproof.

With this device in position in the bottle 40 the liquid can be easily and conveniently dispensed by manipulating the cap 17 by the grasp 19 in the aforementioned manner.

When the bottle has been emptied my device 45 may be pulled off and applied to a fresh bottle in the same manner.

Since various modifications may be made in the construction of my device without departing from the spirit of my invention I do 50 not wish to limit myself to the details shown and described.

What I claim is:—

1. A bottle closure, comprising a tapered tubular body open at both ends adapted to be 55 inserted into the mouth of said bottle, spring actuated closing means for the outer end of said tubular body, means for operating said closing means, a series of parallel annular projections on said tapered tubular body and 60 resilient means slidably mounted on said tapered tubular portion for engaging the neck portion of said bottle, said resilient means cooperating with said parallel annular projections to firmly and tightly hold said tubular body in place.

2. A bottle closure comprising a tapered tubular body formed with a dispensing spout and adapted to be passed into the neck of the bottle, resilient tightening means movably mounted on said body and adapted when said body is passed down into the bottle to be compressed between the said body and the inner face of the mouth of said bottle, means on said body cooperating with said resilient means to retain said body in operative position, a manually operated sealing lid for said dispensing spout and means in said body operatively connected to said manually operated sealing lid for picking up and removing the paper cover of the bottle prior to mounting said bottle closure.

In testimony whereof I affix my signature.
ROBERT HAGEBUSCH.
